UNITED STATES PATENT OFFICE.

JOSEPH ALBERT YOUNG AND GEORGE YOUNG, JR., OF BELLEVUE, IOWA.

GLASS LENS.

1,088,863.

Specification of Letters Patent. Patented Mar. 3, 1914.

Application filed September 15, 1913. Serial No. 789,868.

To all whom it may concern:

Be it known that we, JOSEPH ALBERT YOUNG and GEORGE YOUNG, Jr., citizens of the United States, residing at Bellevue, in the county of Jackson and State of Iowa, have invented certain new and useful improvements in Glass Lenses, of which the following is a specification, reference being had therein to the accompanying drawing.

10 This invention relates to signs and has special reference to that type of illuminating signs wherein the casing is provided with a number of openings arranged to suit the design and lenses are held in these 15 openings to be illuminated by a suitable electric or other light placed within the casing.

The principal object of this invention is the production of a simple and efficient 20 means for holding the lens in a locked engagement with the casing whereby the lens will be prevented from rotating.

With the above and other objects in view as will be hereinafter apparent, the invention consists in general of certain novel 25 details of construction, combinations of elements and arrangements of parts herein-after fully described and illustrated in the accompanying drawing and specifically 30 claimed.

In the accompanying drawing, like characters of reference indicate like parts in the several views, and: Figure 1 is a view from the rear of a lens showing it in position in a 35 casing, the view illustrating the position of the lens at the moment of its insertion. Fig. 2 is a vertical section through the lens shown in Fig. 1. Fig. 3 is a view of the casing prior to the insertion of the lens. Fig. 40 4 is a perspective view of the lens removed from the casing. Fig. 5 is a view of the lens and a portion of the casing showing the lens locked in position. Fig. 6 is a side elevation of the device showing the casing in 45 section and illustrating how the casing may yield to accommodate the locking lug.

For the purpose of illustrating the device there has been shown in the present case a single lens and a small portion of one wall 50 of a casing. It will be obvious, however, that the lens may be of other shapes or arrangements and that the lenses will be arranged in some particular order on the casing according to the design of the sign to be 55 constructed.

The casing is indicated at 10 and this cas-

ing is provided with one or more openings 11, which are circular in general form but which have spaced notches 12 extending into the body of the metal of which the casing is 60 formed.

The lens to be used in connection with this device is provided with a body portion 13 preferably concavo-convex and having a rearwardly projecting annular rib 14. Furthermore, the rib 14 is so arranged that an annular shoulder 15 is formed exterior of this rib. Projecting from the rib 14 are a series of spaced lugs 16 which are equal in number to the notches 12 and similarly 70 spaced. These lugs 16 have curved sides 17 while their inner ends are spaced from the shoulder 15. By placing a lens within one of the openings 11 so as to allow the lugs 16 to rest within the notches 12 the lens will be 75 so positioned as to force the casing between the inner ends of the lugs 16 and the shoulder 15, since by rotating the lens 13 the casing will ride upon the curved sides 17 of the lugs 16 for facilitating the placing of 80 the casing between the lugs and shoulder. When it is desired to build up a sign with these lenses a suitable design is formed by stamping a series of openings through the metal and the lenses are then inserted in 85 such a manner that the lugs 16 will pass through the notches 12 after which the lenses are rotated to the position shown in Fig. 5 so that the lugs 16 will engage over the edge of the opening 11, by means of the 90 curved sides 17. The rib 14 is provided with an integral square locking lug 18 positioned between two of the lugs 16, whereby after the casing is positioned between the lugs 16 and shoulder 15 the locking lug will 95 be positioned within one of the notches 12 for preventing the lens from rotating. In this manner it will be seen that the lens cannot be lost from the casing 10 after the casing is positioned between the lugs 16 and 100 the shoulder 15 by rotating the lens whereby the locking lug 18 will be positioned within a notch 12.

There has thus been provided a simple and efficient device of the kind described 105 and for the purpose specified.

It is obvious that many minor changes may be made in the form and construction of this invention without departing from the material principles thereof. It is not 110 therefore desired to confine the invention to the exact form herein shown or described,

but it is wished to include all such as properly come within the scope of the appended claim.

When it is desired to place a lens in position, the lugs 16 will be positioned and operated as above set forth. As the lens is rotated the casing will ride upon the curved sides 17 of the lugs 16 thereby forcing the locking lug 18 into firmer engagement with the casing 10. When the casing 1 rests between the shoulder 15 and the lugs 16, the locking lug 18 will have forced the casing, which is formed of sheet metal, to yield as shown in Fig. 6. As soon as the lens is rotated approximately one-sixth of a revolution, the locking lug 18 will rest within one of the notches 12 as shown in Fig. 5 at which time the casing will spring to its normal flat position whereby the lens will be held in position by the lugs 16 and against rotation by the locking lug 18.

Having thus described the invention, what is claimed as new, is:-

In a sign of the class described, a casing provided with an opening, said casing provided with a plurality of notches adjacent said opening, a lens carried by said casing,

said lens provided upon its rear portion with an annular rib, a plurality of lugs formed upon said rib, said lugs each provided with a curved side, a shoulder formed upon said lens at a spaced distance from the inner ends of said lugs, said lugs adapted to be positioned within said notches, and said lens adapted to rotate whereby said casing will ride upon said curved sides of said lugs for positioning said casing between said lugs and said shoulder for holding said lens in engagement with said casing, said annular rib provided with an integrally formed squared locking lug, said locking lug positioned between said first mentioned lugs, said locking lug adapted to fit in one of said notches for holding said lens against rotation, whereby said lens will be held securely in engagement with said casing.

In testimony whereof we hereunto affix our signatures in presence of two witnesses.

JOSEPH ALBERT YOUNG.
GEORGE YOUNG, JR.
